UNITED STATES PATENT OFFICE.

LOUIS E. SPEER, OF BROOKLYN, NEW YORK.

NOZZLE.

Application filed June 6, 1925. Serial No. 35,282.

This invention relates to douche nozzles and more particularly to such nozzles as are adapted for cleansing and irrigating and conveying liquid medicaments to the interior 5 portions of the vaginal cavity.

With ordinary methods of irrigation, the interstices formed by the overlapping folds of the membranous walls of the cavity are not reached by the jets and sprays used, and 10 it has previously been proposed to dilate or distend the interior tract by means of separate instruments whereby the medicaments may reach every portion of the folds of the membrane. Devices have also been proposed 15 which are adapted to be associated with the douche nozzle to effect such dilation, but these devices have generally involved mechanical movements and have been expensive of manufacture and difficult of cleansing 20 or when impositive in their nature that is, not involving mechanical movements to effect dilation of the vagina they have lacked durability.

The present invention seeks to provide a 25 combined dilator and douche nozzle which shall be impositive in its nature, may be effectively used without distress or danger to the inexperienced individual user and which shall not impede the outflow of 30 the cleansing or healing medium, while at the same time it shall be capable of thorough cleansing and be practical from the standpoint of ease and cheapness of manufacture. Accordingly a nozzle 35 is provided having a separate dilator adapted to be slipped thereon and which may be secured together by means of a perforated tip, the nozzle and dilator being preferably made of metal and being easily separable 40 for cleansing and sterilization and the dilator being so formed as to effect dilation of the vaginal cavity in an easy and gentle manner to the requisite degree.

In order that the invention may be clearly 45 understood the same will now be described more fully with reference to the accompanying drawings illustrating a preferred embodiment thereof, in which:

Figure 1 is a view in side elevation of the 50 vaginal douche and dilator according to the present invention.

Figure 2 is a fragmentary view, partly in 55 section, on an enlarged scale, showing the manner in which the dilator is positively secured on the douche nozzle by means of the perforated tip.

Figure 3 is a transverse sectional view of the dilator taken in the plane indicated by the line 3—3 in Figure 1 and looking in the direction of the arrows.

The douche nozzle is formed as a tube which is indicated in general at *a* and is formed with a passage *a'* longitudinally thereof for the passage of the fluid medicament. At one end the tube *a* is formed with a receiving portion *a²*, over which may be thrust a loose or flexible tube leading from a container (not shown) for the medicament. The other end of the tube is threaded interiorly as at *a³* to receive the outwardly threaded end *b* of a perforated tip *b'*. Between the threads on the portion *b* and the perforated portion of the tip there is formed a portion of reduced diameter *b²* which is normally adapted to be disposed outwardly of the end of the tube *a* for the reception of a shoulder *c* formed on the end *c'* of the dilator *c²*. The dilator *c²* is formed of two spaced annular portions *c', c³* of an interior diameter just sufficient to receive the tube *a* and spaced or connected by radially disposed fins *c⁴* shown in the illustrated embodiment as four in number equally spaced from one another and provided with gently rounded outer surfaces as indicated at *c⁵*, whereby no sharp edges are afforded which might tend to injure sensitive membranes. The outer marginal surfaces of the webs *c⁴* are also gently tapering from end to end rising from a substantially small height adjacent the annuli *c'* and *c³* and gradually increasing in height to the highest point, midway between the annuli, as shown clearly in Figure 1, whereby the nozzle may be inserted within the opening of the vagina and the latter gradually expanded or dilated as the nozzle advances, to open the interstices between the folds and permit an exposure of all of the interior surface to the fluid medicament. While the walls of the cavity are thus distended by the webs *c⁴*, provision is made in the spacing of the webs for the medicament to flow freely outwardly therebetween, whereby the continuous discharge of the medicament from the perforated tip is not impeded.

It will thus be seen that a durable nozzle has been provided comprising, in general, a tube, perforate tip, and dilator, which are readily separable for cleansing and sterilization. The nozzle may be formed of any

convenient material although it is deemed advantageous to form both tube and dilator of metal which will not be affected by the high temperature used in sterilization.

5 Various modifications in the configuration, composition and manner of associating the component elements of the douche nozzle may occur to those skilled in the art and are to be deemed to be within the scope of the 10 present invention.

What I claim is:

1. In a douche nozzle, in combination, a tube, a separable perforate tip, a separate dilator comprising spaced annuli having an 15 interior diameter sufficient to receive the tube and spaced curved webs extending between the annuli, and means to secure the dilator in position over the tube.

2. In a douche nozzle, in combination, a

tube, a separable perforate tip, a separate 20 dilator comprising spaced annuli having an interior diameter sufficient to receive the tube and spaced curved webs extending between the annuli, and means to secure the dilator in position over the tube through the instrumentality of the tip.

3. In a douche nozzle, in combination, a tube, a separable perforate tip, and a separate dilator comprising spaced annuli having 25 an interior diameter sufficient to receive the tube and spaced curved webs extending between the annuli, one annulus being formed with an inwardly extending shoulder to overlie one end of the tube and be retained by the perforate tip.

35 This specification signed this 5th day of June A. D., 1925.

LOUIS E. SPEER.
